UNITED STATES PATENT OFFICE.

WALTER A. HEINRICH, OF ST. LOUIS, MISSOURI, ASSIGNOR TO W. N. MATTHEWS AND BROTHER, INC., OF ST. LOUIS, MISSOURI, A CORPORATION OF NEW MEXICO.

SPRAY-GUN.

1,382,641.

Specification of Letters Patent. Patented June 28, 1921.

Application filed June 1, 1920. Serial No. 385,653.

To all whom it may concern:

Be it known that I, WALTER A. HEINRICH, a citizen of the United States, residing at St. Louis, Missouri, have invented a certain 5 new and useful Improvement in Spray-Guns, of which the following is a full, clear, and exact description, such as will enable others skilled in the art to which it appertains to make and use the same, reference 10 being had to the accompanying drawings, forming part of this specification, in which,—

Figure 1 is a side elevational view of my spray gun;

15 Fig. 2 is a vertical sectional view through the same.

Fig. 2^a shows a solid nozzle employed for producing a circular pattern.

Fig. 3 is a top plan view.

20 Fig. 4 is a front elevational view.

Fig. 5 is an enlarged view of the nozzle and nipple arranged in the front end of the barrel.

Fig. 6 is a detail view of the manner of 25 securing the springs to the valves.

This invention relates to a new and useful improvement in spray guns for paint or other liquids or powders, the object being to provide a simple, cheap construction which 30 will deliver a round or fan-shaped pattern onto the surface to be covered.

In the construction shown in the accompanying drawings, the liquid or powder to be sprayed passes through a nipple having 35 a constricted delivery opening and screwed into the front end of the barrel while the air or gas passes around the nipple and is delivered around the nipple at angles which produce and form a spray having a circular pattern. If the nozzle is provided with angularly disposed openings through which air will pass, the point of intersection of the air passing through these openings being in front of the nipple, the atomized 40 spray will be flattened out to assume a fan-shape. By adjusting the nozzle so that these flattened air blasts are one above the other, the fan-shaped pattern will be horizontal, whereas a quarter turn locating the angularly-disposed air-blast openings in a horizontal plane will produce a vertical sheet 45 of fan-shaped pattern. These angularly-disposed blast openings are shown in Figs. 2, 4 and 5, while in Fig. 2^a, I have shown a 55 solid form of nozzle, the latter producing a

circular pattern. These nozzles are preferably interchangeable on the same gun.

In the drawings, 1 indicates a casting having a reduced portion at the junction of the barrel and handle, in which reduced portion is an opening 2 by which the gun may be hung upon a nail or other support when not in use. 3 is a handle which may be of any suitable material, said handle being formed with a longitudinally disposed opening through which passes a tube 4 screwed into the casting 1 and communicating with a conduit or passage 5 in the casting. 6 is a washer seated against a shoulder in the lower end of the handle and against which washer impinges a nut 7 whereby the handle is held in position, said nut 7 having a threaded extension 8 forming a nipple for the attachment of a flexible tube leading from some suitable source of compressed air, 65 or other gas, supply.

The casting 1 is provided with a downward extension 1^a having a flat rear face to coöperate with a tapered flat face formed on the handle, whereby when the nut 7 is 80 screwed home, the handle is held firmly in position, the flat coöoperating faces just referred to preventing the handle from turning. This extension 1^a is also provided with a trigger guard 1^b which not only serves to 85 protect the trigger but affords a rest or support for the operator's finger in manipulating the gun.

The trigger 10 is bifurcated at its upper end and pivoted at 11 on each side of the 90 casting 1, the prongs of the bifurcation having forwardly extending members 11^a which are pivotally connected to the legs 12^a preferably guided in grooves in the side walls of the casting 1, and the pivotal connection between the arms 11^a and the legs 12^a possesses 95 sufficient lost motion or play, as for instance, a longitudinally disposed slot in the arms 11^a, indicated by dotted lines in Fig. 1, may be provided so as to enable the parts to articulate without binding.

The saddle 12 extends across the barrel of the gun, as shown in Figs. 3 and 4, and is normally held upwardly by means of a plunger 13 arranged on the upper end of the 105 stem of a valve 14, which valve coöperates with a seat in a threaded valve plug 15 screwed into the casting 1. The valve and plunger are held upwardly by means of a spring 16 and in order that the spring may 110

be withdrawn when it is desired to clean the parts and the saddle is removed and the valve plug 15 backed out, the upper convolution of spring 16 is squeezed in and around 5 the flaring projection extending from the bottom face of valve 14.

The air passage or conduit 5 before referred to opens into the lower end of the bore in casting 1 which receives the spring 10 16, and when the valve 14 is unseated by being depressed, the air will pass upwardly through and around the spring beyond the valve, through ported openings 15^a in the valve plug and into the conduit 5^a communicating therewith and leading to the chamber formed by the nozzle 17 having threaded connection with the barrel of the gun whereby it may be rotatably adjusted. This nozzle has two straight openings 17^a 20 drilled or bored therethrough, said openings being diametrically opposite each other and arranged at an angle so that the blasts of air issuing therefrom will have their point of intersection immediately in front 25 of the constricted opening in the nipple 18 through which the liquid to be sprayed passes. By this construction, it will be noted that the air passing around the cylindrical portion of the constricted mouth of 30 the nipple 18 will form a cylindrical target if a solid imperforate nozzle, such as shown in Fig. 2^a, is employed, and by adjusting the nozzle 17 inwardly and outwardly the size of the pattern at a given distance from 35 the surface to be sprayed can be regulated.

If the form of nozzle shown in Figs. 2, 4 and 5 is employed, *i. e.*, where there are diagonally disposed openings through which issue jets, or blasts, of air whose point of 40 intersection is located in advance of the mouth of the nipple 18, it will be obvious that these jets of air will flatten out the cylindrical pattern and produce a fanlike pattern which may be vertical, if the openings 45 are in horizontal plane, or horizontally disposed if the openings 17^a are in a vertical line.

A flexible pipe (not shown) is connected to a threaded hollow nipple 20 screwed into 50 the casting 1 and preferably between the barrel and the trigger. This nipple has a threaded ring 21 screwed into its lower end which forms a seat or bearing for spring 22 which spring holds a valve 23 up to its 55 seat, which seat is formed at the upper end of the nipple plug 20 and opens into a conduit or passage 24 leading to the centrally arranged nipple 18 whereby a central flow of the liquid to be sprayed is thus attained. 60 25 indicates a bushing having a beveled tight joint at its lower end, said bushing being mounted in a plug 26 screwed into the casting 1.

27 is a plunger secured to the valve stem

of valve 23, and as shown in Fig. 2, this 65 plunger terminates slightly below the cross-piece 12 of the saddle member whereas the plunger 13 bears directly under the saddle member and holds it in its elevated position. 70

The operation of the device is very simple. A flexible pipe leading from some suitable source of air or gas supply is connected to the nipple 8, a flexible pipe (not shown) leading from some suitable source 75 of liquid supply, which liquid is to be sprayed by means of the gun, is connected to the nipple 20. The operator now holds the trigger, first opening the air valve and admitting air around the end of nipple 18 80 and by a continued pull on the trigger, the valve 23 is opened so as to admit a supply of fluid through the nipple 18. If the solid nozzle 17, shown in Fig. 2^a, is employed, a cylindrical pattern of the spray will be 85 made; but if the nozzle provided with openings 17^a, as shown in Figs. 2, 4 and 5, is employed the spray pattern will be fan-shaped either horizontally or vertically disposed, depending upon the adjustment of 90 the nozzle 17.

The purpose of sequentially operating first the air valve and then the liquid valve is to insure the flow of air before the admission of liquid to the nipple 18 and following the shutting off of the supply of liquid to said nipple 18. In this manner, a solid stream of liquid which might flow from the gun, if the valves were simultaneously opened or if the liquid controlling 100 valve was opened slightly in advance of the air valve, is avoided, and likewise when the trigger is released, the nipple 18 will be practically cleared of liquid at or near its mouth so that there is little liability of the 105 liquid leaking therefrom.

What I claim is:—

A spray gun comprising the combination of a casting formed with conduits or passages for compressed air or gas and a liquid or powder, valves in control of said passages, means for operating said valves, a nipple for supplying a central flow of liquid or powder, and an adjustable nozzle around said nipple for projecting a blast of air or gas around the forward end or mouth of said nipple, said nozzle being formed with diametrically opposite and angularly disposed straight openings in its conical forward end leading from the interior of the nozzle for directing angularly disposed blasts of air against two sides of the central blasts from the nozzle and immediately in front of said nipple. 110 115 120

In testimony whereof I hereunto affix my 125 signature this 27th day of May, 1920.

WALTER A. HEINRICH.
